UNITED STATES PATENT OFFICE

1,928,738

PUMP

William E. Pike, Winston-Salem, N. C.

Application February 21, 1931. Serial No. 517,617

1 Claim. (Cl. 221—95)

This invention relates to pumps, and more particularly to pumps designed primarily for use in dispensing gasoline.

An important object of the invention is the provision of means whereby a single compressed air supply tank may be utilized in supplying compressed air to a plurality of supply tanks, making it unnecessary to provide an independent compressed air supply tank and valve, for each gasoline line supply tank.

Another object of the invention is to provide means for automatically controlling the operation of the device, when the filling hose have been removed for directing gasoline to an automobile gasoline tank or similar place of deposit.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is an elevational view of a pump and system, constructed in accordance with the invention.

Figure 2 is a sectional view through the valve body of the valve employed in controlling the passage of air to the gasoline supply tanks of the system.

Figure 3 is an enlarged sectional view through one of the foot valves of the pump.

Figure 4 is a sectional view through the filling hose supporting hook of the pump, illustrating the mercury of the switch in a position to break the circuit to the magnet of the valve operating mechanism.

Figure 5 is a sectional view through the hook.

Referring to the drawings in detail, the system with which my pump is used, comprises a storage tank 5 which is supplied with gasoline, through the filling pipe 6, the pipe being closed by means of the usual screw cap 7.

A vent pipe indicated by the reference character 8 also communicates with the storage tank 5, and extends an appreciable distance above the ground surface in which the tank 5 is buried, the end of the pipe 8 being supplied with branch pipes 9.

The reference character 10 designates the discharge pipe leading from one of the storage tanks 5, it being understood that several of these stor-

age tanks are employed in a system, to contain the various grades of gasoline, such as standard gasoline, high test gasoline, or the like, however, since these tanks and pipes leading therefrom are identical, the construction and operation of the pump when only one storage tank is used, will be described in detail. The pipe 10 is supplied with a valve housing 11, at the lower end thereof, the valve housing accommodating the foot valve 12, which operates to admit gasoline to the discharge pipe 10, and at the same time prevent air pressure entering the tank 5, through the pipe 10. As shown, the pipe 10 extends to a point above the ground surface, where it is supplied with a cap 13 to normally close the pipe.

Connected with the pipe 10, is a pipe 14 that connects with the pipe 15 which has its lower end extended into the supply tank 16, the construction of the tank 16 being such that gasoline will be siphoned from the tank 5, to enter the supply tank 16, to maintain the tank 16 full at all times.

The reference character 17 designates a discharge pipe, which extends into the supply tank 16, and is supplied with a foot valve 18 at its lower end, the foot valve permitting gasoline to flow from the supply tank 16 into the pipe 17, and at the same time prevent the return of gasoline into the tank 16, through the pipe 17.

Communicating with the pipe 17 is a pipe 19 to which the upstanding pipes 20 are connected, the pipes 20 extending to the meters 21, which are of a well known type, the meters acting to measure the gasoline passing through the pump. Valves 22 are mounted on the hose 23, the valves being so constructed that they may be readily and easily controlled by the operator, to control the passage of gasoline through the hose. The valves 22 are of such construction that they may be hung on the hooks 24. Each of these hooks 24 includes a hollow body portion pivotally mounted near the front end thereof, as at 25, so that the rear ends of the hooks will automatically swing downwardly, when the valve members 22 are removed therefrom, the valve members 22 acting to normally tilt the hooks 24 so that the front or hook ends thereof lie below the rear ends.

Mercury containers 26 are mounted in the hook members 24 and are formed with openings to receive the wires 27 that lead to the coil 28 of the magnet, to be hereinafter more fully described, the wires acting to provide a circuit between the hooks 24 and magnet which of course is in circuit with a suitable source of electricity supply.

The coil 28 is mounted on the valve 29 and is constructed to attract the armature of the magnet, which is mounted on one end of the arm 31, the arm 31 being pivotally mounted on the 5 supports 32 of the magnet. One end of the arm 31 extends downwardly as at 33, where it contacts with the upper end of the lever 34, the lower end of the lever 34 being connected with the rod 35 that extends into the valve 29. This rod 35 10 carries the valve 36 which seats against the valve seat 36'.

The valve member 37 is mounted on one end of the rod 35', which rod extends into the valve 29, at the opposite end thereof, the valve being 15 adapted to seat against one end of the valve 29 under normal conditions, the valve 36 being open. The coiled spring 38 engages one end of the valve 29 and acts to normally urge the valve rods 35' and 35 in one direction to hold the valve 36 20 unseated under normal conditions, while the valve 37 remains seated, and since the valves 36 and 37 are mounted on independent rods, it will be obvious that the valve 36 may move a greater distance than the valve 37, allowing the air to 25 exhaust rapidly.

Forming a part of the valve 29, is a chamber 39 which is disposed between the valve seats against which the valves 36 and 37 engage, the 30 valve chamber 39 being in communication with the valve chamber 40, through openings 41. Extending into one end of the valve 29, is a compressed air supply pipe 42 which is in communication with a suitable source of compressed air supply not shown. Mounted on the pipe 42, is an 35 air pressure reducing valve 43, which is adapted to maintain a predetermined pressure on the valve 37 at all times.

Gauges 44 are mounted on the compressed air pipe 42 and are disposed on opposite sides of the 40 air pressure reducing valve 43, to register the air pressure at both sides of the valve 43. Air passes from the chamber 39, into the supply tank 16, through the pipe 45, there being provided a branch pipe 46 connected with the pipe 47, for 45 directing air under pressure into an adjacent gasoline supply tank. As air enters the gasoline supply tanks 16, it is obvious that gasoline will be forced from the tanks through the discharge pipes thereof, from where the gasoline will pass 50 through the meters and into the hose, to be directed to the place of deposit.

The operation of the pump is as follows:

Assuming that it is desired to dispense a quantity 55 of gasoline, and the valves 22 are hanging on their hooks. The valve through which a particular type of gasoline passes on being dispensed by the pump, is removed from its hook, whereupon the hook swings upwardly, the mercury in the mercury container 26, moving to complete the 60

circuit between the wires 27, which in turn energize the coil 28, drawing the armature 30 into engagement with the coil. As the armature 30 is drawn downwardly, the end 33 of the arm 21 moves the lever 34 to force the rod 35 inwardly, causing the valves 36 and 37, to take positions as shown by Figure 2 of the drawings.

Air now passes from a suitable source of compressed air supply, through the pipe 42 and into the chamber 39, from where it passes through the pipes 45 and 47, into the supply tanks 16.

It follows that gasoline is forced upwardly through the discharge pipes 17, and through the hose and valve, which has been operated by the attendant, to release gasoline. As the gasoline passes through the meters 21, the number of gallons will be registered, so that the attendant may determine the 80 85 90 95 100 105 110 115 120 125 130 135 140 145 150 number of gallons dispensed. When the proper amount of gasoline has been dispensed, the valve is hung on its hook, to the end that the seat of the valve and hose will tilt the hook and cause the mercury in the mercury container 26 to flow into the forward end of the container, where it disengages one of the wires 27, breaking the circuit.

When the circuit to the coil 28 has been broken, the spring 38 operates to force the rod 35 to its initial position, seating the valve 37 and unseating the valve 36. The air pressure in the tanks 16 will now exhaust through the pipe 45, chamber 37, valve chamber 40 and pipe 48, that is shown as connected with the vent pipe 8. While I have shown and described two supply tanks, it is obvious that any number of supply tanks desired, may be used and controlled by a single air control mechanism or pump.

I claim:

A fluid dispensing system comprising a storage tank, supply tanks, pipes leading from the storage tank to the supply tanks, filling the supply tanks, a valve member including a body portion, said body portion having an enlarged bore and having chambers at the ends of the bore, means for establishing communication between the supply tanks and the bore of the valve, to admit air to the supply tanks, a valve rod extending through the bore, valves on the valve rod and adapted to seat against the ends of the bore controlling the passage of air through the bore, a pipe for supplying air under pressure to the bore, a lever at one end of the valve body and contacting with the valve rod, a pivoted arm disposed adjacent to the lever, and engaging the lever for operating the lever and rod, electrically controlled means for operating the arm moving the lever and valve rod to admit air to the supply tanks, and discharge pipes connected with the supply tanks for directing liquid from the tanks.
